[57] **CLAIM**

A breast surgery tool, as shown and described.

DESCRIPTION

FIG. 1 is a top plan view of a breast surgery tool showing my new design in use, wherein the broken line shown of a person's hands is for illustrative purposes only and forms no part of the claimed design;

FIG. 2 is a top perspective view thereof;

FIG. 3 is a side elevational view;

FIG. 4 is a top plan view thereof;

FIG. 5 is a rear elevational view;

FIG. 6 is a front elevational view thereof;

FIG. 7 is a side elevational view, opposite that shown in FIG. 3; and,

FIG. 8 is a bottom plan view thereto.

FIG. 3.

FIG. 4.

FIG. 5.

FIG. 6.

FIG. 7.

FIG. 8.
